FUEL FEEDING SYSTEM

Louis Beeh, Springfield, Mass.

Application September 5, 1941, Serial No. 409,663

12 Claims. (Cl. 123—139)

1

This invention relates to a fuel feeding system for internal combustion engines of the solid injection type. In engines of the type to which the invention relates an injector directed into the combustion space of the engine is provided with an injection valve which is opened in response to the increasing pressure of the liquid fuel supplied thereto by a suitable fuel pump and is closed by the action of a heavy spring or other resilient means in response to a reduction of pressure in the fuel supply line. This decrease in injection pressure is normally the result of the opening of a spill valve or by-pass passage which opens into the pressure chamber of the pump and thereby immediately and sharply reduces the pressure in this chamber. Because of the high pressures of the order of 4000# per square inch in the fuel line there is a reaction of this pressure in the direction of the reduced pressure in the pump chamber and a resultant tendency of the fuel in the line to reverse its direction of flow and move in the direction of the pump chamber. The reaction causes the discharge valves between the pump chamber and the fuel line to close sharply so that the fuel in the injection line is still under a high pressure.

Reactions are set up due to the inertia of the moving column of fuel and due to the natural resilience of the supply line, such that reversals of the pressure wave in the supply line are set up so that the wave again moves in the direction of the injection valve, tending to open the same slightly and causing a slight dribble at the nozzle orifice.

The fuel so improperly atomized and improperly timed with respect to the engine cycle is not properly consumed and is therefore objectionable from the standpoint of thermal efficiency, but it also tends to carbonize around the nozzle orifice and is therefore also objectionable from the point of view of mechanical efficiency.

In some instances these pressure waves travel back and forth several times in the fuel line, causing not only secondary but tertiary injections.

There have heretofore been many attempts made to overcome the above-mentioned difficulty and prevent this dribble at the fuel nozzle. The most common of these is to provide a skirt on the discharge valve of the pump, which skirt upon the closure of the valve functions as a piston or plunger, moving in the direction of the pump chamber, and is therefore effective to increase the total volumetric capacity of the fuel line and other connections between the pump

2

chamber and the injection nozzle. Such a system is effective to reduce the static pressure within the fuel line and therefore avoid any oozing of fuel from the nozzle due to this static pressure. Such a system, however, is not effective to reduce the dynamic forces which cause the secondary and tertiary injections which are due to successive reversals of the direction of flow in the line, which occur upon the final closure of the discharge valve whether provided with a withdrawal skirt or not, due to the piling up of the pressure in the vicinity of the discharge valve and the reaction of this pressure back through the line in the direction of the injection valve.

15 It is among the objects of the present invention to overcome the above-mentioned difficulties and prevent the violent oscillations of the fuel remaining in the fuel column.

The secondary and tertiary injections above-described leave the fuel lines, if they are not all of the same capacity, under varying residual pressures and cause the next succeeding injection to occur at other than the predetermined time, adding thereby to the roughness of the engine due to improper timing.

It is a further object of the present invention to overcome the above-mentioned difficulty by providing a system in which a constant predetermined residual pressure may be maintained 30 in the fuel line between the pump chamber and the injection valve, to the end that the after dribble above described is prevented and also the oscillations in the fuel line are smoothed out at both the beginning and the end of the injection, thereby providing a smoother engine operation.

The above and other objects and features of the invention will be apparent to those skilled in the art from a consideration of the following detailed description taken in conjunction with the 40 accompanying drawings in which:

Fig. 1 is a vertical section of a portion of the fuel feeding device constructed in accordance with the present invention and also showing a portion of the internal combustion engine to which the device is connected.

Fig. 2 is a vertical section through a portion of a fuel feeding device showing a modified form of the invention.

Fig. 3 is a view similar to Fig. 2 to show a further modification.

Referring to the drawing, reference numeral 1 indicates a conventional internal combustion engine of the solid injection type having an injector 2 mounted in the head thereof, which injector is 55 provided with one or more nozzle orifices 3 di-

3

rected into the combustion space 4. The nozzle orifice 3 is closed by a valve 5 of conventional construction and having as usual a shouldered portion 6 which is adapted to be acted upon by the pressure of fuel supplied thereto by way of the supply line 7 to move the valve in an opening direction against the action of the spring 8.

Fuel is supplied to the injector 2 by means of a pump 9 having a plunger 10 mounted to reciprocate in a cylinder 11 and adapted to uncover a supply port 12 in its lowermost position whereby fuel from the feed chamber 13 may flow into the pump chamber 14 when piston 10 is in the position shown in the drawing, while the upper end of the cylinder 11 is closed by a plate 15, 16 provided in the central portion thereof. The plate 15 is held in position against an interior shoulder in the pump body 17, and also against the upper end of the pump cylinder 11, by means of a bushing 18 which is provided with external threads coating with internal threads in the upper end of the pump body 17 to the end that an annular boss 19 upon the end of the bushing 18 will press upon the peripheral portion of the plate 15 when the parts are in the position shown.

The bushing 18 is provided with a central cylindrical bore 20 in which a discharge valve 21 having a cylindrical sleeve portion 22 is adapted to reciprocate, being biased in the direction of plate 15 by the spring 23. The lower end of the valve 21 is provided with an annular boss 24 of considerably less external diameter than the external diameter of the sleeve portion 22. The annular boss 24 is adapted to seat upon the plate 15 in closing relation to the orifice 16 so that when the valve is in the closed position, as shown, a relatively small area thereof is exposed to the pressure within the pump chamber 14, while an additional area is exposed to the pressure of the fuel in the annular discharge chamber 25 surrounding the valve on the discharge side of the orifice 16.

The chamber 25 communicates by way of passages 26 in the bushing 18 with an annular chamber 27, which chamber is directly connected to the fuel supply line 1. For convenience of construction the annular chamber 27 may be formed in a block 28 separate from the bushing 18 and firmly attached thereto in a manner hereinafter to be described.

The valve spring 23 is adjustable by means of a screw plug 29 which extends through an internally and externally threaded nipple 30 which projects from the upper end of the bushing 18. The screw plug 29 has a central passage 31 to permit the escape of any fuel which leaks around the valve 21 into the cylindrical bore 20. A nut 32 coating with the external threads on the nipple 30 holds the block 28 firmly in position.

In the operation of the device when the parts are in the position as shown, with the plunger 10 in its lowermost position, fuel is supplied under some pressure by way of the supply chamber 13, and the pump chamber 14 is filled with fuel. As the plunger 10 moves upwardly the intake port 12 as well as the by-pass port 33 are closed by the upper edge of the plunger 10 and further upward movement of the plunger 10 places the fuel under sufficient pressure to cause the same to lift the valve 21 and flow through the supply line 7 to the injector 2. As the pressure rises sufficiently to overcome the heavy spring 8, the injection valve 5 opens and fuel is injected through the nozzle orifice 3 into the engine cylinder. As the plunger

4

10 approaches the end of its discharge stroke, a helical lip 34 on the end of the plunger 10 uncovers the by-pass port 33, permitting the fuel from the pump chamber 14 to flow into the by-pass chamber 35 and thence back to the fuel supply tank by way of pipe 36; thus there is a sharp reduction in the pressure within the pump chamber 14 and within the discharge chamber 25. The pressure in the supply line 7 is sharply reduced, the injection valve 5 tends to close and the fuel in the supply line 7 which was formerly flowing at high velocity toward the injection valve now tends to flow in a reverse direction toward the fuel pump. This reversal of flow sets up a pressure wave in the direction of the pump which, if the discharge valve 21 were a conventional check valve, would tend to cause the valve to seat sharply due not only to the action of the spring 23 but also to the dynamic pressure of the fuel in the supply line. This would be true regardless of whether or not the check valve were provided with a withdrawal skirt.

By the present construction the reversal of flow in the supply line 7 has no tendency to close the discharge valve but on the contrary acts upon the valve to move the same in an opening direction so that the pressure wave tends to become dissipated through the discharge orifice 16, the pump chamber 14 and thence to the by-pass port 33. Thus the reversal of flow in the fuel line does not build up a pressure on the discharge side of the valve which could possibly react back in the direction of the injection valve and cause a secondary injection. It will be understood that the spring 23 being weaker than the spring 8, any pressure wave present in the fuel line and having sufficient force to open either of the valves, will necessarily dissipate itself through the discharge valve of the pump rather than through the injection valve of the engine.

Referring to Fig. 2 which shows only the parts directly associated with a modified form of the discharge valve, it will be obvious from the drawing that the construction and operation of this form is closely analogous to the form shown in Fig. 1 except that a small valve 40 is provided in the discharge valve 41 and is adapted to control an orifice 42 which extends through the face of the discharge valve 41. As in the prior construction a spring 43 biases the discharge valve 41 in a closing direction and a spring 44 surrounding a stem 45 on the valve 40 normally maintains the latter valve in a closed position. A set screw 46 is mounted for adjustment in the upper closed end of valve chamber 47 and projects downwardly therefrom to contact with the upper end of the stem 45 of the valve 40 whenever the discharge valve 41 has been lifted to a point slightly below the uppermost limits of its opening movement.

The operation of the form shown in this figure is similar to the operation of the form shown in Fig. 1 since it will be understood that fuel placed under pressure by the pump plunger will lift the discharge valve 41 from its seat and cause fuel to flow to the engine by way of passage 48, the cutoff of the fuel supply and the prevention of oscillations of fuel in the fuel line being effected in the same manner. The form here shown, however, has the additional advantage that at high speeds the valve 41 moves upward further in its opening direction than at low speeds and as these high speeds are attained the stem 45 of the valve 40 contacts the set screw 46, thereby permitting a slight flow of fuel through the passage 42 into

the valve chamber 47 and thence through a return passage 49.

This arrangement compensates for a further defect of injection systems of the type to which the invention relates in that for any given setting of the fuel control rod of such pumps the volume of the fuel supplied by the pump at each pressure stroke thereof tends to increase as the speed increases. This is particularly true in connection with pumps of the type in which the quantity of the fuel supplied by the pump is controlled by a helical lip on the end of the plunger, which lip varies the time of opening and closing of the by-pass passages of the pump to the end that angular movements of the pump plunger will cause the by-pass passage to be opened sooner or later during the discharge stroke of the pump plunger and accordingly supply a smaller or greater quantity of fuel to the engine for each working stroke thereof. In all such constructions where one or more of the ports of the pump are positioned in the side walls of the pump cylinders and controlled by the plunger, the leakage around the plunger into these ports will be greater when the pump plunger is moving slowly than it will be when the pump plunger is moving at high speed. For this reason the pump will tend to supply a greater charge at high speed for each stroke thereof than it will supply when operating at a relatively low speed. This increase in the unit charge of fuel supply at high speeds is the reverse of the relationship that is actually required inasmuch as a slight reduction in the unit charge for high speeds is desirable.

By the form of the invention disclosed in Fig. 2 an automatic compensation is made for the unit charge supplied by the pump at high speed since at low speed the discharge valve 41 does not move upwardly far enough for the stem 45 to contact with the set screw 46 and therefore the full charge for any given setting of the control rod of the pump is supplied to the combustion space of the engine. However, as high speeds are attained the valve 41 moves further in its opening direction until the valve 40 is opened by contact of the end of stem 45 against the set screw 46 and a slight compensating leakage is thereby permitted during the short period in which the discharge valve 41 is in its uppermost position.

It will also be seen that this form of the invention provides a safety escape in the event that the fuel nozzle 3 should become clogged or the injection valve 5 should become stuck so that fuel cannot be discharged into the clearance space of the engine, for in either case pressures cannot be built up in the fuel line 7 such as would cause breakage of the pipes or connections because under such conditions the valve 41 would be forced to its uppermost position, causing the valve 40 to open and relieve the pressure in the fuel line by way of the orifice 42, the valve chamber 47 and return passage 49.

Referring to the form shown in Fig. 3 it will be seen that the construction is similar to that shown in Figs. 1 and 2, except that the discharge valve 50 is provided with an enlarged shouldered portion 51 of greater diameter than the sleeve portion 52 of the valve and that this enlarged portion on the valve makes a loose sliding fit with a slightly enlarged portion 53 of the cylindrical bore 54. As in the construction previously described, the valve 50 is adapted to close the discharge port 55 of the pump chamber

56 to permit the flow of fuel to the engine during the discharge stroke of the pump plunger, the fuel passing by way of vertical passages 57 and cross passages 58 to the discharge nipple 59 which is connected to the fuel supply line leading to the engine cylinder as disclosed in Fig. 1. However, in this construction the valve chamber 60 is connected directly to the fuel supply line by way of an orifice 61 connecting with cross passage 58 at a point which is preferably in line with the passage through the discharge nipple 59 which is connected to the fuel supply line in the usual manner. In this construction the pressure in the pump chamber 56 during the pressure stroke of the pump plunger lifts the valve 50 against the action of spring 62, permitting fuel to flow to the engine. Since, however, the surface area in the rear of the valve which is exposed to the pressure in the fuel line is almost but not quite equal to the area exposed to the pressure on the face of the valve, the upward movement of this member is maintained within predetermined limits even though the spring 62 is not fully compressed. If now the pressure on the lower face of the valve 50 is decreased by reason of the opening of the spill valve of the pump plunger during the discharge stroke thereof, then the pressure upon the rear face, being momentarily greater, will act to move the valve in a closing direction. The same movement, however, tends to withdraw the fuel from the region in the rear of the valve and adjacent the fuel supply line 7 so that the first movement of any oscillation or reversal of direction of flow in the fuel supply line is in the direction of the valve chamber 60, whereas the displacement in the opposite direction tends to displace the fuel in the direction of the pump chamber 56 during the closing movement of the valve. Should the valve reach its full closed position during the period in which there is a continued surge of fuel from the line in the direction of the pump, this surge will first tend to dissipate itself in the valve chamber 60 and thereafter surge as a pressure wave in the direction permitted by cross passage 58 and vertical passages 57, where the pressure wave having access to a slightly greater area or pressure surface will tend to lift the valve slightly and dissipate itself through the pump chamber 56. In this structure violent oscillations of the valve 50 are prevented while at the same time oscillations of the fuel within the fuel supply line which normally result in secondary and tertiary injections are dissipated.

It will be apparent that in each of the embodiments of the invention free communication is permitted through the system between the seat of the injection valve 5 and the by-pass passage 33 the instant this passage is opened by the lip 34 during the upward movement of the pump plunger. No motion of any mechanical part is required to effect or complete this communication since the only valve between the pump and the injection valve is, and remains, in open position at this time. This is important since the desired reduction in the static pressure of the line must take place in a period of a few microseconds.

Each of the embodiments of the invention also provide a construction in which a constant residual pressure is maintained in the system after the pressure has been reduced to a predetermined minimum. Thus, in contradistinction to some prior systems which sought to obtain free communication between the pump and

the nozzle at the instant injection is terminated by providing a continuous communication at all times, the present invention permits such free communication at the desired instant yet prevents communication at times when undesired, such as during the suction stroke of the pump. Communication between the pump and the rest of the system during the suction stroke would permit fuel to be withdrawn from the line to the pump instead of from the suction side of the pump. The pump would thus be totally ineffective as a metering device. The maintenance of the residual pressure in the line is desirable to prevent rapid evaporation of fuel in the nozzle which is heated from the combustion space of the engine, and the formation of vapor pockets which would also interfere with the accurate metering of the fuel charge.

In each of the embodiments shown the volume of the connections between the pump and the seat of the injection valve is reduced upon a reduction of pressure in the fuel line rather than increased. This reduction in volume compensates for the greater reduction in pressure adjacent the pump as compared to the reduction in pressure adjacent the injection valve. This difference in pressure in different parts of the line due to the inertia of the fuel column would normally result in a strong surge of fuel from the portion of the line close to the nozzle, as the inertia is overcome and the fuel accelerated toward the pump. By providing a reduction in volume in the region of the greatest reduction of pressure the pressure differences along the line are less and the ram effect greatly reduced. Furthermore, since the valve may open again after its initial closing in response to pressure in the line any secondary surges in the line are dissipated through the pump in the same way as the initial pressure drop. For this purpose a very slight opening of the valve suffices. In most prior art systems the drip prevention means has tended to increase the surging of fuel in the line rather than diminish it.

It will also be observed that since the closing movement of the discharge valve is against the residual pressure of the line the valve closes gradually and is not slammed against its seat.

While there have been herein described various embodiments of the invention other embodiments within the scope of the appended claims will be apparent to those skilled in the art from a consideration of the embodiments shown and the teachings hereof. Accordingly it is desired that the appended claims be given a broad interpretation commensurate with the scope of the invention within the art.

Having thus described the invention, what is claimed as new is:

1. In a fuel supply system an injection pump including a pump cylinder, a plunger reciprocative within said cylinder, said cylinder being provided with inlet and discharge ports, means for relieving the pressure in said pump chamber in the course of the discharge stroke of said plunger, a discharge valve normally closing said discharge port and operable by the pressure in said pump to open said discharge port, a fuel supply line leading from said discharge valve, an injector having a nozzle orifice connected to said supply line, a pressure operated injection valve for closing said orifice, said discharge valve having a pressure area exposed to the pressure in said supply line effective to bias said valve in an opening direc-

tion, whereby the reversal of flow in said supply line upon the release of pressure in said pump acts to maintain said discharge valve in open position to vent fuel from said supply line to the pump side of said discharge valve until the pressure in said line drops to a predetermined value below the pressure required to operate said injection valve.

2. A fuel supply system including in combination a fuel feeding device, a fuel injector, a fuel supply line connecting said fuel feeding device and said fuel injector, a valve controlling communication between said fuel feeding device and said supply line, said valve having surface area exposed to the pressure in said feeding device when the valve is in closed position and being operable by the pressure in said device to open communication between said device and said supply line upon an increase in pressure in said device and to close such communication in response to a decrease in such pressure, said valve also having a surface area exposed to the pressure in said line and acting to move said valve in an opening direction in response to a predetermined pressure in said line.

3. A fuel supply system including in combination a fuel injection valve opening in response to the pressure of the fuel supplied thereto and closing upon a predetermined decrease in such pressure, a pump, a fuel supply line connecting said pump and said injector, a movable member positioned between said pump and said injector, said member being operable in response to an increase in pressure within said pump to open communication between said pump and said supply line and to simultaneously increase the total volumetric capacity of said line in proportion to the increase in pressure, means for suddenly relieving the pressure within said pump, and means associated with said movable member for maintaining the same in open position until after a predetermined decrease in the pressure within said supply line.

4. A fuel feeding system including in combination a fuel injection device, a fuel pump, a supply line for conducting fuel from said pump to said injector, a valve positioned between said pump and said injector, said valve having a pressure area exposed to the pressure in said pump when the valve is in closed position and also having a further pressure area exposed to the pressure in said line, said areas being effective upon predetermined increases in pressure in either said pump or said supply line to move said valve in an opening direction, and resilient means for biasing said valve in a closed direction, whereby predetermined increases in the pressure in said pump cause said valve to open and permit the flow of fuel to said injector and whereby pressure in said line acts in an opening direction on said valve to permit the flow of fuel in a reverse direction upon the decrease in pressure in said pump, thereby maintaining in said line a predetermined pressure below the injection pressure during periods when the pump pressure is below the injection pressure.

5. A fuel feeding system including in combination a fuel injection device, a fuel pump, a supply line for conducting fuel from said pump to said injector, a valve positioned between said pump and said injector, said valve having a pressure area exposed to the pressure in said pump when the valve is in closed position and also having a further pressure area exposed to the pressure in said line, said areas being effective upon prede-

terminated increases in pressure in either said pump or said supply line to move said valve in an opening direction, resilient means for biasing said valve in a closed direction, and means to adjust the tension of said resilient means, whereby predetermined increases in the pressure in said pump cause said valve to open and permit the flow of fuel to said injector and whereby pressure in said line acts in an opening direction on said valve to permit the flow of fuel in a reverse direction upon the decrease in pressure in said pump, thereby maintaining in said line a predetermined pressure below the injection pressure during periods when the pump pressure is below the injection pressure.

6. A fuel feeding system including in combination a pump, an injector, a fuel supply line between said pump and said injector, a pressure responsive valve between said pump and said injector controlling the flow of fuel through said line and operable in one direction to open communication between said pump and said injector, and means associated with said valve for relieving the pressure in said line when said valve approaches the limit of its opening movement.

7. A fuel feeding system including a pump, an injector, a fuel supply line between said pump and said injector, a pressure responsive valve between said pump and said injector controlling the flow of fuel through said line and operable in one direction to open communication between said pump and said injector, means forming with said valve an auxiliary chamber in restricted communication with said line, whereby upon the increase of pressure upon the face of the valve the volumetric capacity of said auxiliary chamber will be proportionately decreased and upon decreases of such pressure the volumetric capacity of said auxiliary chamber will be increased in proportion to the decrease in pressure in said line.

8. In combination, a fuel pump having a pump chamber, a fuel supply line leading from said pump chamber, a valve controlling communication between said chamber and said supply line, said valve being opened in response to pressure in said pump chamber, means to suddenly relieve the pressure in said pump chamber, and means to maintain said valve in open position after the relief of pressure in said pump chamber to vent fuel from said line to said chamber until the pressure in said line drops to a predetermined value.

9. In combination, a fuel pump having a pump chamber, a fuel supply line leading from said pump chamber, a valve controlling communication between said chamber and said supply line, said valve being opened in response to pressure in said pump chamber, means to suddenly relieve the pressure in said pump chamber, and means responsive to the pressure in said line for holding said valve in open position to vent fuel from said line to said chamber until the pressure in said line has been reduced to a predetermined value.

5 10. The combination, with a fuel injection system of the type having a fuel injection pump, a closed fuel injection nozzle and a fuel supply line connecting said pump and nozzle; of a valve controlling communication between said pump and said nozzle, said valve opening in response to the pressure on the pump side thereof, and also opening in response to pressures above a predetermined value in said line between said valve and said nozzle said predetermined value being less than the pressure required to open said nozzle.

15 11. In a system of the type including a high pressure liquid pump, a pressure operated atomizing device, and a supply line connecting said pump and said device, the combination of a valve controlling communication between said pump and said device, means to suddenly relieve the pressure on the pump side of said valve, said valve opening in response to pressure on the pump side thereof and remaining open upon the relief of the pressure on said pump side until the pressure between said valve and said nozzle falls to a predetermined value below the pressure required to operate said atomizing device.

20 25 30 35 12. In combination a high pressure liquid pump, a pressure operated atomizing device, a supply line providing a passage between said pump and said atomizing device, a valve controlling said passage, said valve being opened in response to the pressure in said pump, means to suddenly relieve the pressure on the pump side of said valve, and means to maintain said valve in open position upon the relief of pressure on said pump side thereof until the pressure between said valve and said atomizing device falls to a predetermined value below the pressure required to operate said atomizing device.
